UNITED STATES PATENT OFFICE.

HERMAN BURGI, OF SPRINGFIELD, MASSACHUSETTS, ASSIGNOR OF ONE-HALF TO
CHARLES H. TENNEY, OF SPRINGFIELD, MASSACHUSETTS.

AUTOMATIC GAS-PRESSURE REGULATOR.

1,346,529.

Specification of Letters Patent. Patented July 13, 1920.

Application filed November 24, 1919. Serial No. 340,428.

To all whom it may concern:

Be it known that I, HERMAN BURGI, a citizen of the United States, and residing at Springfield, county of Hampden, State 5 of Massachusetts, have invented certain new and useful Improvements in Automatic Gas-Pressure Regulators, of which the following is a specification.

This invention relates primarily to means 10 for automatically controlling the passage of gases through a flue, and is particularly adapted to control the pressure or vacuum of hot gases in the chimney or arch of a seat- 15 ing in a steel furnace, coke oven, a retort bench, or anything that requires a control of hot gases. It will be observed, however, from the following description of the structure and operation, that many of its novel features are adapted for other uses for con- 20 trolling the passage of fluids and, therefore my claims are not to be taken as limited to the particular uses of those features stated. It has been found very difficult to provide satisfactory means for automatically regu- 25 lating the discharge of hot gases through a flue by, and in accordance with, the pressure or vacuum in the chamber from which they come, so as to accurately regulate the pressure or vacuum in the chamber. The 30 flue must be made or lined with fireproof refractory material, and it is very desirable that the valve or damper itself shall be heat resisting so as to avoid frequent replacements and repairs, but ordinarily to do this 35 would make the structure too cumbersome and hard to work to be practical. Furthermore, even in the forms of dampers and valves which have been found practical, too much power has been required to operate 40 them to make it possible to utilize the direct action of a pressure or vacuum float or other direct pressure or vacuum control, and it was necessary to make use of an outside source of power which was merely controlled 45 by the pressure mechanism. This, aside from the extra expense introduced other elements likely to cause inaccuracy in result, and was likely to get out of order. My invention is intended to avoid these defects, 50 and embodies a valve or damper which can be made of fireproof refractory material, and which can be so easily moved to open or close the flue that it may be connected to, and directly operated by, the pressure or 55 vacuum float or other pressure operated de-

vice. The novel features will be understood from the following description and claims, taken in connection with the drawing. In the drawing:

Figure 1 is a side view of my invention 60 applied to a typical installation of a gas retort;

Fig. 2 is a vertical section through a portion of the outlet flue and the pressure float mechanism showing my invention; and 65

Fig. 3 is an end view of the valve or damper itself.

In these drawings 10 is the retort chamber of the gas retort, and in which it is desired to maintain a regulated gas pressure 70 or vacuum. The gases pass out through an outlet flue 11, which has a lining 12 of fireproof material. Extending from one side of the flue 11 there is a valve chamber 13, which is also lined with fireproof refractory 75 material 14. As shown, the bottom wall 15 of this valve chamber is flat and horizontal, extending at right angles from flue 11, and the top wall 16 is similarly shaped. At the outer end of the valve chamber 13 there is 80 a suitable closure 17 provided with a central bearing opening 18 for the sliding operating rod 19 for the valve 20. The valve 20 extends transversely of the valve chamber 13, and is rounded throughout the greater portion 85 of the surface on a curve in cross section, which may be substantially circular, making a semi cylindrical part of the valve. The valve is preferably made of fireproof refractory material, and has at one point a 90 projection 21, one side of which is a tangent to the curve where it leaves the cylindrical portion. The material of the valve just beyond this projecting portion 21 is removed or omitted to such an extent that the valve 95 will be substantially balanced in position on any portion of the curved part to which it may be turned, and thus it will stand in any adjusted position without the use of outside force to hold it there. The valve 20 is 100 so placed in the valve chamber 13 that when the projecting portion 21 is turned to rest on the floor 15, it forms a projection in line therewith across the flue opening in 11. To make proper closing connection with the 105 walls of the flue 11, the lining 12 is cut away at 22 on a curve from above, leaving a ledge against which the tip end of the valve strikes, and which serves as a stop for it. The valve 20 on the side opposite the pro- 110

jection 21 has in its upper portion for almost 90°, a central slot 23 which extends slightly beyond the center of the curved outer surface, and at this point a pin or rod 24 may be passed through an eye in the end of the operating rod 19, whereby a pull or push in rod 19 will tend to roll the valve or damper 20 on the floor 15, causing the projection 21 to roll forward toward the flue 11 finally closing it, as shown in Fig. 2, or to roll back to the position shown in Fig. 1, where the point of the projection is at the top of the valve chamber and at the wall of the flue, leaving an open passage for the gases.

15 This substantial balance of the valve and its action in simply rolling on a smooth surface, makes its operation very easy and requires very little power.

The automatic means for controlling the action of the valve as shown, consists of an outlet pipe 25 leading from the chamber 10 of the gas retort and terminating above the liquid in the float chamber 26. An arm 27 is hinged at 28 and carries at one end the weight 29 which may be varied in accordance with the pressure or vacuum which it is desired to maintain. It is pivoted at its other end 30 to a rod 40 carried by the float, and is there connected to an arm 41 which is 20 pivotally connected to the rotary mechanism 42, whereby a rise or fall of the float member in the pressure device will turn the rotary member 42. This rotary member is in turn connected by link arm 43 to the end of 25 the valve operating rod 19 so that the turning of 42 will roll the valve and cause it to open or close the flue in accordance with the direction of movement. It will be understood that where reference has been made 30 to maintaining a definite pressure or vacuum in the apparatus, reference was had to pressures either above or below atmospheric. It will further be understood that the weights 29 are intended simply to counter- 35 balance more or less the weight of the floating member of the pressure or vacuum device which, of course, tends to move downwardly.

Having thus described the invention what 40 is claimed as new and desired to be secured by Letters Patent is:

1. A valve structure comprising a conduit having a passageway therethrough and a valve chamber extending laterally therefrom, a rolling valve resting and rolling on the bottom of said valve chamber and having a projection adapted to extend across and close said passageway when the valve is rolled to one end of its path of travel and 45 to open said passageway when rolled in the other direction.

2. A valve structure comprising a conduit having a passageway therethrough and a valve chamber extending laterally therefrom, a substantially balanced rolling valve

resting and rolling on the bottom of said valve chamber and having a projection adapted to extend across and close said passageway when the valve is rolled to one end of its path of travel and to open said 70 passageway when rolled in the other direction.

3. A valve structure comprising a conduit having a passageway therethrough with a valve chamber extending therefrom laterally of the same width as said passageway and having a bottom or floor, a valve extending across said valve chamber having a transversely curved portion adapted to roll on said floor and a projecting portion 75 adapted to extend across said passageway in contact with the walls thereof to close the same when said valve is rolled to proper position.

4. A valve comprising a semi-cylindrical portion and a tangential projecting portion, the material on the side including the projection being only such as will substantially balance that on the other side of the center of the semi-cylindrical portion whereby the 90 valve will roll easily carrying the projection through a considerable arc and will unaided remain in adjusted position.

5. A pressure and vacuum control mechanism comprising a fluid conduit having a 95 valve chamber extending laterally therefrom, a substantially balanced rolling valve resting and rolling on the bottom of said valve chamber and having a projection adapted to extend across and close said conduit when said valve is rolled to one end of its path of travel, means connected to said valve for rolling it and extending to the exterior of said valve chamber and automatic pressure or vacuum controlled means for 100 operating said rolling means.

6. In a device of the class described the combination with a chamber adapted to contain hot gases under pressure or vacuum, of an outlet flue lined with refractory material 110 and having in one side a transversely extending valve chamber lined with refractory material, a substantially balanced rolling valve of refractory material resting and rolling on the bottom of said valve chamber 115 and having a projecting portion adapted to extend across and close said flue when the valve is rolled to one end of its path of travel, pressure operated mechanism connected with said chamber, and means so connecting said valve with said pressure or 120 vacuum operated mechanism as to automatically roll said valve to open and close said flue by and in accordance with the pressure or vacuum in the chamber.

7. In a device of the class described the combination with a chamber adapted to contain hot gases under pressure or vacuum, of an outlet flue lined with refractory material and having in one side a transversely 130

extending valve chamber lined with refractory material, a valve formed of refractory material extending transversely of said valve chamber and resting on the bottom thereof rounded in the form of a continuous arc in cross section throughout the greater portion of its outer surface but having a tangential projection adapted to extend across and close said flue, the material of said valve being so distributed as to substantially balance it on any part of its curved surface, and pressure or vacuum controlled automatic means for rolling said valve to open or close said flue. 10

In testimony whereof I affix my signature. 15

HERMAN BURGI.
